UNITED STATES PATENT OFFICE.

CHARLES VALLONE, OF BUFFALO, NEW YORK, ASSIGNOR TO BARCALO MANUFACTURING COMPANY, OF BUFFALO, NEW YORK.

HOLDING MEANS FOR THE SLIDING SIDES OF CRIBS.

1,179,685.

Specification of Letters Patent. Patented Apr. 18, 1916.

Application filed March 25, 1915. Serial No. 16,929.

To all whom it may concern:

Be it known that I, CHARLES VALLONE, a citizen of the United States, residing at Buffalo, in the county of Erie and State of New York, have invented a new and useful Improvement in Holding Means for the Sliding Sides of Cribs, of which the following is a specification.

This invention relates to improvements in children's cribs of that kind which have vertically sliding sides or side railings adapted to be retained in an elevated position for confining a child in the crib, and to be lowered to facilitate the placing of the child in the crib; and more particularly the invention relates to cribs of this kind in which the sliding sides are provided at the end portions thereof with clutches or devices which coöperate with the guides for the sliding sides for holding the sides up in the position to which they are raised.

One object of this invention is to provide means of practical and desirable construction whereby the clutches at the opposite ends of the side can be readily operated by one hand, so that it is only necessary to use one hand to raise and secure or release and lower the side. Thus a person holding a child in one arm can operate the side with the other hand without having to lay down the child.

Another object is to provide a holding or securing mechanism for the side which is of simple and inexpensive construction, is convenient for operation, is not cumbersome, and does not detract from the neat appearance of the crib.

In the accompanying drawings: Figure 1 is a side elevation of a crib embodying the invention. Fig. 2 is a fragmentary sectional elevation, on an enlarged scale, of the upper portion of one of the sliding sides and its guides. Fig. 3 is a sectional plan view thereof in line 3—3, Fig. 2. Fig. 4 is a detail section in line 4—4, Fig. 2.

A A represent the end frames of a child's crib or bed, said frames being connected by a bottom frame B or by horizontal side rails in any usual or suitable manner, and C is one of the vertically sliding side frames or railings of the crib. A metal crib is shown in the drawings in which each side or side railing C consists of upper and lower hori-

zontal rails c and c' connected by spaced vertical rods c², and is arranged to slide up 55 and down on vertical guide rods D which are suitably secured at their upper and lower ends, as by brackets d, to the end frames, and pass through guide holes or eyes d' at the ends of the upper and lower rails of the 60 side frame. The crib as thus far described is of a construction commonly employed in metal cribs. The top rail c of the side consists preferably of a metal tube.

E E represent holding devices or clutches 65 arranged at the end portions of the top rail c of the side and slidably engaging the guide rods D for holding the side C when raised. Each of the clutches shown consists of a lever which extends lengthwise above the top 70 rail and is movably connected at its inner ends thereto to swing toward and from the rail and is provided with a hole e through which the adjacent guide rod D passes. The hole e is of such size and shape as to allow 75 the lever to slip on the guide rod and permit the side to be raised or lowered when the outer end of the lever is moved toward the top rail, and to grip the rod and prevent the lever and side from sliding downwardly 80 thereon when the lever is in an inclined position, as best shown in Fig. 2. The lever is provided at its inner end with ears or lugs e' which straddle the top rail and are connected by a pin or rivet f which extends 85 through elongated slots f' in the top rail. A spring g connected to the inner end of the lever and extending into a hole g' in the top rail normally holds the lever in the inclined position shown in Fig. 2, in which it 90 grips the guide rod. When the side C is raised the clutch levers will yield downwardly or toward the top rail against the action of the springs g, as indicated by dotted lines in Fig. 2, far enough to slip on the 95 guide rods, and the side can therefore be slid upwardly on the guide rods without the necessity of actuating the clutches by hand. When the side is released the clutch levers will assume their inclined position under 100 the action of the springs g and the frictional contact of the levers with the guide rods, and the levers will grip the guide rods and hold the side against downward movement in the position to which it is raised. The 105 side cannot be lowered unless the clutches

are released by moving the free ends of the clutch levers toward the top rail.

For thus actuating or releasing the clutches to permit the lowering of the side the following means are preferably employed: H H represent two levers or handles which are arranged at opposite sides of one of the vertical rods c^2 of the side to which they are suitably pivoted, as by a rivet h passing through the rod c^2 and through holes in the lower ends of the levers which are disposed respectively at the inner and outer sides of the rod. The levers extend upwardly from their pivotal connection and their upper ends, which project into the tubular top rail c through holes h' in the bottom thereof, are connected to the adjacent or inner ends of two bars, links or the like I which extend lengthwise in the top rail. One of these links I is connected at its opposite or outer end to the cross pin f of the clutch lever E at one end of the side, and the other link I is similarly connected to the clutch lever at the opposite end of the side. As shown, the upper ends of the levers or handles H engage loosely in holes or eyes i in the inner ends of the links I, this connection enabling the ready assembling of the parts; and the upper portions of the levers are bent outwardly and upwardly, thus affording a comfortable desirable hold for the hand. By pressing the levers or handles H toward each other the links I will be drawn inwardly and swing the clutch levers to their released position, thus permitting the movement of the side on the guide rods D. The clutch levers E shown tend to swing to their gripping position by frictional contact with the guide rods when it is attempted to lower the side and they will bind tighter as the downward pressure is increased. Very light springs g can therefore be used with the clutches and these light springs enable the operating levers to be actuated with very little exertion.

The levers or handles H arranged as described can be grasped and operated by one hand to release the two clutches E at the opposite ends of the side, and as the levers or handles are located substantially midway between the ends of the side, they constitute a handle or device by means of which the side can be conveniently and easily raised and lowered by the hand grasping the levers, so that it is not necessary to use both hands either in raising or lowering the side. The operating links or connections from the clutch levers to the operating handles are concealed within the tubular top rail of the side, and the clutches are inconspicuous, while the operating levers or handles constructed and arranged as shown lend an ornamental appearance to the side, so that the holding or securing means do not detract from the neat appearance of the crib.

While the particular construction shown and described is desirable, the invention is not necessarily limited thereto as both the clutches and operating levers or handles could be of different form or construction and still be within the intent and spirit of the invention. 70

I claim as my invention:

1. The combination of a crib side, guides on which the same is arranged to slide, clutches coöperating with said guides for holding the side from downward movement, clutch operating levers pivoted on said side between the ends and below the top thereof and extending upwardly from their pivots in position to be actuated by one hand, and a connection from each of said levers above its pivot to one of said clutches. 75

2. The combination of a crib side having a tubular rail, guides on which the side is arranged to slide, clutches at the ends of said rail coöperating with said guides for holding the side from downward movement, clutch-operating levers pivoted on said side between the ends thereof and below said tubular rail, and connections between said operating levers and said clutches arranged within said tubular rail. 80 90

3. The combination of a crib side having a tubular rail, guides on which the side is arranged to slide, clutches at the ends of said rail coöperating with said guides for holding the side from downward movement, clutch-operating levers pivoted at their lower ends on said side below said tubular rail with their upper ends projecting into said rail, and connections in said tubular rail between said levers and said clutches. 95

4. The combination with a crib side and guide rods adjacent to the ends of said side on which the side is arranged to slide up and down, of friction clutches mounted on the end portions of said side to swing vertically and coöperating with said guide rods to frictionally hold the side in different positions of adjustment, each of said clutches comprising a lever extending lengthwise along the side in the vertical plane thereof and having a hole through which the adjacent guide rod passes, clutch-operating means arranged between the ends of the side and connected to the clutches, and springs for moving said clutches to grip the guide rods. 110 115 120

5. The combination with a crib side having a horizontal rail and guide rods adjacent to the ends of said side on which the side is arranged to slide up and down, of clutches mounted on the end portions of said side and coöperating with said guide rods to hold the side from movement, each of said clutches comprising a lever extending lengthwise along said horizontal rail 125 130

and having ears projecting from the sides thereof which straddle said rail and are movably connected thereto to permit the clutch to grip and release the guide rod, clutch operating means located between the ends of said side, and connections from the same to the lever ears of said clutches.

Witness my hand this 23rd day of March, 1915.

CHARLES VALLONE.
